(57) **CLAIM**

The ornamental design for a sink, as shown and described
herein.

DESCRIPTION

FIG. 1 is a top front perspective view of a sink showing our
new design;

FIG. 2 is a top plan view shown on an enlarged scale thereof;

FIG. 3 is a front elevation view shown on an enlarged scale
thereof;

FIG. 4 is a right side elevation view shown on a greatly
enlarged scale, the left side being a mirror image thereof;
and,

FIG. 5 is a partial cross-sectional view shown on an even
greater enlarged scale taken along line 5—5 shown in FIG.
2 thereof.

The jagged lines, especially in FIGS. 3-6, are the result of
computer-generated drawings, and they do not denote
jagged lines, edges, etc. as part of the claimed design.
